UNITED STATES PATENT OFFICE.

JOHN BITHELL, OF NEWTOWN, ENGLAND.

LOCK OR FASTENING FOR RAILWAY AND OTHER CARRIAGE DOORS AND THE LIKE.

1,076,544.

Specification of Letters Patent.

Patented Oct. 21, 1913.

Application filed March 19, 1912. Serial No. 684,897.

To all whom it may concern:

Be it known that I, JOHN BITHELL, a subject of the King of Great Britain and Ireland, and resident of Newtown, Wigan, 5 England, have invented certain new and useful Improvements in Locks or Fastenings for Railway and other Carriage Doors and the like, of which the following is a specification.

10 This invention refers to railway carriage door and like locks or fastenings which automatically lock the doors and keep them securely fastened while the train is in motion, and has for its object to provide a 15 novel construction of fastening which is pneumatically operated by a fan, or other means for compressing air, controlled by the wheels of the carriage.

According to the invention a box-like casing 20 is let into the jamb of the doorway or into the framework of the carriage adjacent to the usual latch-like fastening. In said casing are two compartments in one of which is arranged a lever and in the other 25 of which is a vane or air-box mounted on a spindle common to the two. In the front of the chamber containing the lever is a slot into which the ordinary latch of the door passes when the door closes. Leading 30 to the chamber containing the air box is a pipe through which air is circulated when the train is in motion to lift or operate the air box which in turn brings the lever into the path of the latch to prevent it being released 35 from the slot to open the door.

Upon the accompanying drawing, Figure 1 illustrates the edge of a door casing or framework with the invention applied. Fig. 2 illustrates a view of the casing with 40 the front removed. Figs. 3 and 4 are vertical cross-sections taken respectively on lines $x-x$ and $y-y$ of Fig. 2. Fig. 5 illustrates a carriage or coach showing an example of how a series of the locks or fastenings may 45 be connected to means for supplying or conducting air to operate the fastenings.

In carrying out the invention a box-like casing is provided comprising a front or face plate a in which is cut the usual slot a' 50 for receiving the latch, and chambers or compartments b , c . Extending through both compartments is a spindle d upon which are mounted the air box e , in the chamber b , and the lever f , in the chamber c . 55 In the floor of the chamber b is an inlet opening b' which permits of air being ad-

mitted to the chamber to act on the air-box while at the top of said chamber b is an outlet or exhaust opening b'' . The air-box and lever are so designed that, in their normal position, they lie as represented in Figs. 3 and 4 respectively. With the parts so arranged and the cover or plate of the casing secured in position the casing is let or fixed into the edge of the framework of the carriage as shown in Fig. 1, that is to say, with the slot a' arranged to receive the latch of the door as in the case of the ordinary plate.

Connected to the opening b' will be a pipe g leading through the framework beneath 70 the carriage, where it may connect to a conduit h , see Fig. 5. Communicating with the conduit is a fan driven from one or other of the wheels, which fan, with the train in motion, will force air through the 75 conduit h into the pipes g , there being one of these latter to each door, to act on the air box e . On the air box being raised or operated, under the force of the air, the lever f is forced and held against the back 80 of the plate a . With the latch extending into the slot a' while the lever f is thus held, the removal of the latch from the slot is impossible as the lever f will prevent the raising or turning of the latch sufficiently to 85 allow it to become clear of the slot in the plate a' . To prevent any undue strain being put on the lever f a stop or block e' is provided in the upper part of the chamber e , against which the lever bears when in 90 its operative position.

The air, after acting upon the air-box will leave the chamber b through the opening b'' and will usually be conducted beneath the carriage through a pipe or air-way i indicated by dotted lines in Fig. 1. This air way i as well as the pipe g will be arranged in the edge of the framing immediately beneath the beading j so as to be readily accessible. When the air pressure 100 in the air-box e diminishes, that is when the train ceases to move the parts will assume their normal position and the lever will be moved clear of the opening a' . While the lever will at all times permit of 105 the latch being passed into the slot a' it will only permit of its removal after the train has stopped.

It will be understood that instead of using a fan for creating the necessary flow of air 110 to the chamber b other and suitable air-compressing means operated by the wheels

may be provided. Also the arrangement and construction of casing, air-box and lever may be modified without departing from the nature of this invention, the chief feature 5 of which is to provide means which may be operated pneumatically from the wheels to prevent the opening of railway carriage doors while the train is in motion and to automatically release the latches of the doors 10 when the train stops to permit of the doors being opened in the ordinary way.

What I claim is:—

1. In combination in railway carriages, means whereby the doors may be latched 15 when closed, means whereby the latches may be prevented being operated to release the doors but which normally lie clear of the latches, further means which, on being operated by the wheels of the carriage, pneumatically operate the said latch-controlling 20 means to lock the door latches, substantially as herein set forth.

2. In means for automatically locking or

securing railway and other carriage doors when the train is in motion, a casing having 25 two chambers let into the framing of the carriage doorway at a point opposite the latch of the carriage door when such door is closed, a lever within one of such chambers, and an air box in the other chamber, 30 an axis to which both the lever and box are connected and about which they are designed to rotate, pipes opening into the chamber containing the air box, and means operated by the carriage wheels for forcing 35 air through the chamber containing the box and thereby operating the box and with it the lever, to prevent opening of the door, substantially as herein set forth.

In witness whereof I have hereunto set 40 my hand in the presence of two witnesses.

JOHN BITHELL.
